US00D508943S

(12) **United States Design Patent** (10) Patent No.: **US D508,943 S**
Slimbach (45) Date of Patent: **** Aug. 30, 2005**

(54) **TYPE FONT**

(76) Inventor: **Robert Slimbach**, 128 Ada Ave. #21,
Mountain View, CA (US) 94043

(**) Term: **14 Years**

(21) Appl. No.: **29/173,113**

(22) Filed: **Dec. 19, 2002**

Related U.S. Application Data

(63) Continuation of application No. 29/118,188, filed on Oct.
25, 1999, now abandoned.

(51) **LOC (8) Cl. 18-03**

(52) **U.S. Cl. D18/24**

(58) **Field of Search D18/24-33; 101/103,
101/368, 398**
